UNITED STATES PATENT OFFICE.

MAE GLINES, OF CHICAGO, ILLINOIS.

DOUCHE APPARATUS AND TOILET ATTACHMENT.

Application filed November 29, 1921. Serial No. 518,624.

To all whom it may concern:

Be it known that I, MAE GLINES, a citizen of the United States, residing at Chicago, in the county of Cook and State of Illinois, have invented new and useful Improvements 5 in Douche Apparatus and Toilet Attachments, of which the following is a specification.

This invention relates to toilet attachments and has for its object the provision of a supporting device designed to be associated with a toilet bowl and upon which a person may lie while taking an enema or a vaginal douche.

15 It is well known that in taking a vaginal douche many women lie at half length within a bath tub so as to avoid cramping the organs which it is desired to irrigate and to allow the water or medicated solution to flow 20 easily and naturally to the desired location so as to effect the result desired.

It is well known that in taking an enema it is generally customary for the person to assume a sitting posture over the stool or 25 toilet bowl. There is however a great drawback to this method as the large intestine becomes cramped, frequently to such an extent as to preclude the passage of sufficient water therethrough to produce the desired 30 result. With these facts in view I have designed the present invention which has for its specific object the provision of a support designed for association with a toilet bowl and having supporting legs, the device being 35 so constructed and arranged as to support a person in an easy and comfortable position with the orifices to be irrigated disposed at such location with respect to the toilet bowl as to cause all water and other matter dis- 40 charged to pass into the bowl, my supporting structure having the advantage of enabling the person to lie in such position that the organs will be normally arranged and will not be displaced in any way so that the 45 full benefit of the treatment may be had.

Another object is the provision of a device of this character which is foldable so that it may be made into a rather small and compact bundle for convenience in storage 50 within a closet or the like when its use is not desired.

An additional object is the provision of a support of this character which will be simple and inexpensive in manufacture, highly efficient in use, durable in service and a general improvement in the art.

With the above and other objects and advantages in view, the invention consists in the details of construction to be hereinafter more fully described and claimed, and illustrated in the accompanying drawings in which,

Figure 1 is a side elevation of my device in set up position ready for use.

Figure 2 is a top plan view thereof.

Figure 3 is a detail perspective view illustrating the mounting of the head-rest.

Figure 4 is a cross-sectional view.

Figure 5 is a detail sectional view showing the clamping means engaging the toilet 70 bowl.

Figure 6 is a plan view of the underside of one end of the device showing the bowl engaging clamps thereon.

Referring more particularly to the drawings the letter A designates a toilet bowl of ordinary construction with which my device is designed to be associated when in use. In carrying out my invention I provide an elongated rectangular frame 10 which is preferably constructed of pipes connected at their corners of course by suitable elbows, though it should be distinctly understood that this frame might be constructed of iron rod or tubing of any kind. In fact it should be distinctly understood that the frame itself might be formed in most any manner as such a detail does not effect the essential features of the present invention. At one end the frame 10 is formed with an inwardly 75 extending curved portion 11 of substantially the same shape as one end of the toilet bowl A. This end of the frame is designed to be held associated with the toilet bowl by means of a plurality of U-shaped spring clips 12 80 which are secured upon the underside of the frame and which are adapted to grippingly 85 engage the top edge of the bowl A.

Pivotedly connected with the other end 13 of the frame is a head-rest formed of a U-shaped frame 14 having the intermediate portion of its arms coiled about the bar 13 as indicated at 15, the terminals of the arms being formed with hooks 16 which engage beneath the side bars of the frame 10 for the 90 purpose of holding the head-rest at a suitable angular inclination with respect to the frame 10. The frame 10 is covered with canvas or other fabric stretched tightly 95 thereover, this fabric being indicated by the numeral 17, and the head-rest is likewise 100 covered with fabric 18 upon which may be 105 110

disposed a suitable pillow or cushion when the device is used.

In order that the end of the device remote from the bowl may be supported, I provide a pair of legs 19 which are pivotally mounted upon the bar 13 and with which are pivotally connected, as shown at 20, brace rods 21 which are in turn pivotally connected with the side bars of the frames 10 as indicated at 22. These bars or rods 21 are formed intermediate their ends with rule joints 23 whereby they may be folded but whereby they will ordinarily be held in extended position.

Secured upon the end of the frame which is disposed in association with the toilet bowl is a sheet of rubber fabric or gum-rubber, if preferred, designated by 24 and this sheet of rubber fabric is provided with a depending apron 25 which is disposed within the curved portion 11 at the end of the frame to serve as a species of conduits or channel which will conduct into the bowl water or discharge falling upon the rubber sheet. If preferred, and it is advisable, I may provide a suitable cushion or padding 26 between this fabric covering the frame and the rubber sheet 24 so that this will not only provide a soft cushion for the person using the device but it will also serve to make an incline in the upper surface of the rubber sheet which will insure the passage of any water or discharge falling thereonto into the bowl so that it cannot run back onto the fabric covering 17.

In the use of the device it will be seen that the legs 19 are swung into downwardly extending position and the brace rods 21 are extended so as to hold the legs rigid. The head rest structure is then so swung as to extend in an inclined direction as indicated in Figure 1 of the drawings whereupon the hooks 16 at the ends of the arms thereof will engage against the side bars of the frame 10 and maintain the angular position of the head-rest. If preferred a pillow may be placed upon the head rest for the accommodation and comfort of the person taking or receiving the treatment. In using the device the person lies upon the supporting structure with the buttocks, or possibly the abdomen in some instances, resting upon the rubber sheet 24 whereupon the organs or orifices to be irrigated will be in proper position with respect to the toilet bowl A. This position is natural and there will be no distortion or displacement of the organs which might interfere with the free passage of the water or medicated solution which is used for douche or enema purposes. When a person is thus disposed upon the device it will be readily apparent that free access may be had to the organ for effecting the treatment thereof. As above stated the rubber sheet 24 is so ar-

ranged as to be always inclined downwardly toward the bowl so as to conduct away any water or matter which might fall thereupon. When the device is not in use it will be readily apparent that the joint 23 may be broken so that the braces 21 may be folded which will of course result in folding of the legs 19 up against the underside of the frame 10. It is also apparent that the head rest structure is swung to lie against the frame 10 and the device is of course disassociated from the toilet bowl. When the device is thus collapsed or folded it is apparent that it may be easily stored in a closet or other place and will occupy but little room.

From the foregoing description and a study of the drawings it will be apparent that I have thus provided a simply constructed and consequently inexpensive device which will be of great comfort and material benefit to persons having occasion to make use of douche or enema treatments, the device having the particularly meritorious feature of insuring that the patient will lie in a comfortable position which will prevent any possible cramping or contraction of any of the organs to be treated.

While I have shown and described the preferred embodiment of the invention, it is of course to be understood that I reserve the right to make such changes in the form, construction and arrangement of parts as will not depart from the spirit of the invention or the scope of the subjoined claims.

Having thus described my invention I claim;

1. A supporting device of the character described comprising a platform like body member provided at one end with supporting legs and a head rest and having its other end cut away and adapted to be engaged upon the upper edge of a toilet bowl, and means depending from the underside of said cut away end for clamping engagement upon the edge of the toilet bowl.

2. A supporting device of the character described comprising a platform like body member provided at one end with supporting legs and a head rest and having its other end cut away and adapted to be engaged upon the upper edge of a toilet bowl, and means depending from the underside of said cut away end for clamping engagement upon the edge of the toilet bowl, said means consisting of spring clips.

3. A device of the character described comprising an elongated fabric covered frame, one end of said frame being inwardly curved whereby to be disposed upon the upper edge of a toilet bowl, a plurality of spring clips mounted upon the underside of said end of the frame and engageable with the edge of the toilet bowl, and supporting legs mounted at the other end of the frame.

4. A device of the character described comprising an elongated fabric covered frame one end of said frame being inwardly curved whereby to be disposed upon the upper edge of a toilet bowl, a plurality of spring clips mounted upon the underside of said end of the frame and engageable with the edge of the toilet bowl, and supporting legs mounted at the other end of the frame, 10 said legs being foldable whereby to lie against the underside of the frame, and a head-rest including a frame pivoted upon the end of the main frame remote from the toilet bowl and including arms terminating 15 in hooks engaging beneath the sides of the first named frame.
5. A supporting device of the character described comprising a platform like body member provided at one end with supporting legs and a head rest and having its other 20 end cut away and adapted to be engaged upon the upper edge of a toilet bowl, and means depending from the underside of said cut away end for clamping engagement upon the edge of the toilet bowl, said cut away 25 end being covered with a sheet of water proof material having a depending apron thereon extending down from the cut away portion of the platform for disposition within the bowl, and a padding beneath said 30 sheet higher at its edge most remote from the cut away end of the platform whereby to make the upper surface of the sheet inclined toward the bowl.

In testimony whereof I affix my signature.
MAE GLINES.
